UNITED STATES PATENT OFFICE

THOMAS B. ELLISON, OF NEW ORLEANS, LOUISIANA

DESIGN FOR AN AUTOMOBILE BODY

Application filed May 1, 1931. Serial No. 39,677. Term of patent 14 years.

To all whom it may concern:

Be it known that I, THOMAS B ELLISON, a subject of the King of Great Britain, and a resident of New Orleans, in the parish of Orleans and State of Louisiana, have invented the new, original, and ornamental Design for an Automobile Body, of which the following is a specification.

Reference is had to the accompanying drawings, forming a part thereof, wherein an essential feature is the inward curve of the upper part of the doors as well as the upper part of the body.

Figure 1 is a side perspective view of an automobile body showing my new design, the opposite side being identical in appearance

Figure 2 is a top plan view of the automobile body shown in Figure 1, the lamps having been omitted for convenience in illustrating the front portion of the body.

I claim:

The ornamental design for an automobile body substantially as shown and described.

THOMAS B. ELLISON.
